Application September 14, 1936, Serial No. 100,706
Renewed October 22, 1937

11 Claims. (Cl. 123—149)

This invention relates to improvements in magneto.

The invention has for an object the provision in a magneto of a housing, having a mounting flange for direct connection to the crankcase of the engine which the magneto is to serve, and a rotor shaft which is mounted in the housing and extends through the flange into the crankcase for connection to an engine-driven member, such as the cam shaft or a gear thereon, together with provisions in the housing of lubricant-conducting passages for supplying lubricant from the engine crankcase to all parts of the magneto which require lubrication.

According to another object of the invention, the rotor shaft is rotatably supported solely by axially-spaced bearings, preferably of the anti-friction type, one such bearing being located adjacent the mounting flange and another adjacent the rotor and all being located on the same side of the rotor and in such position that they communicate with the crankcase and are lubricated automatically therefrom, sealing means being provided between the rotor and the nearest bearing to keep the lubricant from the rotor and other parts of the magneto.

According to another object of the invention, the rotor shaft, rotatably supported and lubricated as above set forth, extends from the mounting flange on the inner side of said housing to a timer case on the outer side of the housing and that part of the shaft which projects beyond the rotor into the timer case serves to actuate the breaker point mechanism.

According to another object of the invention, the rotor shaft which extends beyond the mounting flange into the crankcase, bears a gear for connection to an engine driven gear in the crankcase and between the gear and mounting flange an impulse driving mechanism is located in position to be lubricated from the crankcase.

Other objects will appear from the following description and will be pointed out in the appended claims.

The invention will be disclosed with reference to the accompanying drawings, in which:

Fig. 1 is a sectional elevational view of a magneto embodying the invention;

Fig. 2 is a cross-sectional view taken on the line 2—2 of Fig. 1 and illustrative of the impulse mechanism;

Fig. 3 is a fragmentary exterior elevational view showing the stationary abutment for the impulse mechanism;

Fig. 4 is a view taken similarly to Fig. 2 but

showing certain parts of the impulse mechanism in different relative positions;

Figs. 5 and 6 are cross-sectional views taken on the lines 5—5 and 6—6, respectively, of Fig. 1; and

Fig. 7 is a fragmentary view taken from the right-hand end of Fig. 1 and showing the timer, the cover for the timer casing having been removed.

Referring to these drawings, the magneto includes a hollow casing or housing 10 (Fig. 1) which in this case is a die casting of non-magnetic metal. This casing has aligned cylindrical openings 11 and 12 leading from opposite ends into an interior chamber 13 in which a magnetic rotor and the cooperating stator are housed.

The stator includes pole pieces 14 made up of soft iron laminations which are embedded one in each of two opposite side walls of the chamber 13 (Fig. 6) during the die casting operation. These pole pieces at their upper ends are interconnected by a core 15 made up of soft iron laminations and carrying the primary and secondary coils 16 and 17, respectively. The ends of core 15 are secured in place by clips 18 and screws 19, as indicated by dotted lines in Fig. 1. The otherwise open upper end of chamber 13 is closed by a cap 20 (Figs. 4 and 6) of molded insulating material, secured by screws 21 to casing 10. This cap contains a metallic socket 22 (Figs. 1 and 4) to receive the spark plug wire and is connected by a spring 23 (Fig. 1) to the high tension terminal 24, which is one terminal of the secondary coil 17. The other terminal of this coil, together with one terminal of coil 16, is grounded by a wire 26 to one of the screws 19. A wire 25 leads from the other terminal of coil 16 to the timer, as will later appear.

The magnetic rotor revolves in the space between the lower ends of pole pieces 14 (Fig. 6) and is fixed to a shaft 27 (Fig. 1) entirely supported, as will later appear, from bearings mounted in the passage 11. The rotor consists of a pair of bar magnets 28 (Fig. 6) mounted in parallel relation, one on each side of the axis of the shaft 27—the latter being recessed to receive the central portions of the magnets. The ends of these magnets of one polarity engage in recesses in a laminated pole shoe 29, and the ends of opposite polarity engage in similar recesses in a similar pole shoe 29. The described assembly of magnets and pole shoes is held between two circular end plates 30 (see also Fig. 1) of non-magnetic metal, suitably clamped together as by rivets 31 and 32.

The timing mechanism is mounted on the circular wall 33 of a cup-shaped casing, the cylindrical wall 34 of which fits in the passage 12 and is held in place by a screw 35. A cover 36, secured by screws 37 to casing 10, closes the outer end of passage 12 and completes an enclosure for the timer. The outer end of shaft 27 projects through a hole in wall 33 into the timer casing and such end, of itself, forms a cam for operating the breaker points 39 and 40,—being cut away, as at 38, to allow these points to close and the uncut peripheral portion holding the points open. The point 40 is adjustably secured and electrically grounded to the wall 33 of the timer case. The point 39 is mounted on a rocker arm 41, made of insulating material and pivoted at a point intermediate its ends on a stud 42 secured to wall 33. One end of this arm 41 rides on the cam end of shaft 27. A spring 43 serves to hold the last named end of arm 41 against the cam end of shaft 27 and also serves to electrically connect point 39 to a terminal 44. The described wire 25 enters the timer case through a hole 45 and is secured to terminal 44. A condenser, indicated at 46 in Fig. 1, is housed in a block 47 of molded insulating material. This block is secured by screws 48 to wall 33 of the timer case and has an extension which carries the terminal 44. The terminals of the condenser are not shown herein but it will be understood that they are connected in the usual and known manner, one to the ground and one to terminal 44. The timer mechanism operates to keep the circuit of the primary coil 16 open for the greater part of each revolution of the magnetic rotor, whereby flux can readily build up in the described magnetic circuit. The surface 38 of shaft 27, once during each revolution, allows the breaker points to close momentarily and then to open again. The points close just before the rotor breaks the magnetic circuit described and open at the time such break occurs.

The timer case has an opening 50 in its wall 33, enabling communication with the bottom of chamber 13 and from the bottom of this chamber a passage 51 extends downwardly and outwardly to the atmosphere. Passage 51 serves to vent the interior of the magneto. It also serves as a drain for the removal of any water and oil that may reach the chamber 13 or timer case. While provision is made for excluding oil from the chamber 13 and timer case and none ordinarily should reach these parts, the drain serves as insurance against trouble from oil should leakage occur from any cause.

The rotor, when turned a little more than 90 degrees from the illustrated position, will establish a magnetic circuit from the magnets 28 through pole shoes 29, pole pieces 14, and core 15 in one direction. When moved a little more than 270 degrees from the illustrated position, the rotor will be positioned to break this circuit and it is this magnetic break that is utilized to produce the spark current. The break which occurs after the rotor has moved 90 degrees from the illustrated position, is not utilized for the production of a spark in this case. Just prior to this first-named magnetic break, the breaker points 39 and 40 engage and close the primary circuit. The flux established in core 14 is thus held against substantial change while the rotor moves into position to create an effective gap between the trailing end of each shoe 29 and the adjacent end of its pole pieces 14. At this time, the leading end of each pole shoe has reached

the opposite pole piece so that a reversal of flux in the magnetic circuit occurs, when the breaker points open. The described arrangement is not novel and is not in any way an important feature of the invention. Other arrangements may equally well be used. 5

The magneto described is given as an illustrative example of one of many suitable types with which the invention may be used. The invention is largely independent of the type of magneto employed and the details, above described, are not to be taken as setting up limitations. 10

The invention is primarily concerned with the mounting of the magneto and its rotor shaft 27 and with the lubrication of the moving parts. 15 The shaft 27 is supported by a pair of axially spaced anti-friction bearings, such as the ball bearings shown in Fig. 1. These bearings, which constitute the sole support for the shaft, are contained within a cylindrical sleeve 52 located in 20 the passage 11, above described. Integral with this sleeve is a mounting flange 53, adapted to be suitably secured, as by the cap screws 54, to a portion of the crankcase c of the engine which the magneto is intended to serve. The flange 53 25 has a finished cylindrical portion 55 to fit into the cylindrical opening o of the crankcase as a pilot and definitely locate and center the shaft 27 with respect to the gear g of the engine, which gear is located within the crankcase and serves 30 to drive shaft 27. A gasket 56 seals the joint between the flange 53 and the mating flange of the crankcase. The flange 53 and sleeve 52 in this case are made of cast iron and are secured to casing 10 by cap screws 53' (Figs. 1 and 4). 35 They are, of course, virtually a part of casing 10, since they are fixed thereto. Their construction as a separate piece is not therefore a necessity.

The ball bearings are of usual form. Their 40 outer and inner races are marked 57 and 58, respectively, and the intervening series of balls 59. The inner races 58 are spaced apart by a sleeve 60 on shaft 27 and the right-hand inner race abuts a shoulder 61 on the shaft. Keyed to 45 shaft 27 is a hub 62, located to the left of the left-hand inner race. The left-hand or inner end of shaft 27, which extends into the crankcase, is threaded to receive a nut 63 and between this nut and hub 62 are a washer 64 and a sleeve 50 65. This nut, through the washer, clamps together the sleeve 65, hub 62, both inner races 58 and the intervening spacer sleeve 60. The outer races 57 are held in place by split retainer rings 66. The sleeve 65 serves to support a gear 55 67 and is slightly longer than the width of the gear so that the latter can turn freely relatively to shaft 27. Gear 67 is driven from gear g and in turn drives the hub 62 and shaft 27 through an impulse mechanism. 60

The impulse driving mechanism may be of any suitable form. In the particular form illustrated, the driving member,—the gear 67,—is provided with an annular recess to receive the spiral drive spring 68 (Figs. 1 and 5) and an 65 annular flange 69 on the hub 62, which constitutes the driven member. The ends of the spring 68 are connected, as shown in Fig. 5, to the members 67 and 69. The member 62 has a flange 70 (Fig. 2) provided with a shoulder 71, against which a pin 72 fixed to the gear 67 is normally held engaged by the spring 68. The flange 62 has pivoted thereto at 73 a member which partially surrounds hub 62, and one end of which forms a latch arm 74 adapted, when shaft 27 is rotat- 75

ing very slowly to engage a stationary abutment in the form of a stud 75 (Figs. 3 and 4) fixed to flange 53, and to thereby temporarily stop the rotation of hub 62. The longer arm 76 of this member constitutes a weight adapted, at higher speeds of rotation of shaft 27, to swing outwardly by the action of centrifugal force and move the latch arm 74 inwardly so that it cannot engage abutment 75. Stops 77 and 78 on arms 74 and 76, respectively, are adapted by abutment with the periphery of hub 62 to limit inward and outward movement of the latch arm and the outward and inward movement of the weight arm, respectively. The free end 79 of the weight arm 15 is adapted to be engaged and moved by the pin 72 to release the latch arm 74 from abutment 75. Thus, after latch arm 74 has engaged abutment 10 75 and arrested the hub 62 and shaft 27, the gear 67 and its pin 72 continue to move in the illustrated direction, winding up spring 68, and the pin eventually reaches the position shown in Fig. 4, wherein it has engaged the end 79 of weight arm 76. Continued movement of pin 72 will move arms 76 and 74 and release the latter from 20 abutment 75, whereupon the spring 68 will draw the hub 62 and shaft 27 suddenly forward until the shoulder 71 on the hub again abuts pin 72.

The lubrication of all moving parts of the magneto is accomplished entirely by oil received from 25 the crankcase c. The oil splash therein lubricates the driving gears and all parts of the impulse driving mechanism and in addition the two sets of ball bearings which form the only ones used for supporting the rotor shaft 27. A hole 30 80 leads from the outer and uppermost part of sleeve 52, at its intersection with flange 53, inwardly and downwardly through the sleeve into the interior thereof at a location between the two bearings. This hole receives oil from the crankcase by splash, or in any other suitable way, and such oil is conducted into the sleeve 52 to lubricate both bearings. Excess lubricant drains back 35 into the crankcase through a hole 81, extending through the sleeve from the lowest part of its interior and leading downwardly into the interior of flange 55, whence it can flow into the crankcase. A suitable sealing means is provided to restrain oil which passes the right-hand or outer bearing from reaching the chamber 13. In this 40 case, the sealing means comprises a rawhide disk 82 secured in a metal cup 83 between the circular face thereof and an annular ring 84 of metal, being held in place by crimping the open end of the cup inwardly upon the ring 84. The cup 45 83 tightly fits in the inner end of passage 11 and the disk 82 closely fits shaft 27. A space is left between this sealing means and the adjacent bearing and from this space a passage 86, formed by an axial groove in the lower peripheral part 50 of sleeve 52, leads to the passage 81, whereby to conduct oil passing through the right-hand bearing back to the crankcase.

The operation of the magneto is the usual one and will sufficiently appear from the foregoing 55 description.

The invention is characterized, among other things, by a direct mounting of the magneto housing on the crankcase, without intervening brackets or mounting bases, and by a mounting 60 of the rotor in the housing in such a manner that all of the rotor bearings are placed in communication with the crankcase to be automatically lubricated therefrom. By simply bolting the mounting flange 53 to the crankcase (after 65 the gear 67 has been properly meshed with the

engine driven gear 9 to secure the proper timing of ignition for the engine) the problem of lubricating the magneto is solved once and for all. The bearings are partitioned off from the rotor by the sealing device 82 and they are located 5 near the mounting flange where they may at all times communicate with the crankcase and receive lubricant therefrom. The bearings are virtually put into the crankcase by the special mounting described. And there are no other 10 parts of the magneto which require lubrication—the timer cam being a fixed part of the rotor shaft and requiring no separate bearing. Thus, the user of the engine need give no attention to the magneto, so far as lubrication is concerned 15 and, so long as he supplies oil to the engine, the magneto parts will be properly lubricated. This arrangement is of great practical importance because it affords excellent assurance that the magneto parts will be properly lubricated without requiring separate attention. An engine operator will rarely neglect to keep the crankcase of his engine supplied with the proper amount of oil but he might easily neglect to oil the magneto. Thus, the present arrangement guards against 20 this possible neglect of duty by the operator and insures that the magneto will be properly lubricated to give the intended long and satisfactory 25 service.

It should also be noted that the magneto bearings are effectively protected from dust and dirt just as much as the engine bearings in the crankcase are. It is necessary to ventilate the magneto in some way and the ventilation provisions offer a possible source for dust and dirt to reach 30 the bearings of the ordinary magneto. But here the magneto bearings are separated from the magneto structure and sealed off by the means 35 82 from that part of the magneto housing that is ventilated.

The ventilation provision—the hole 51—is of 40 novel form and thought to be important. The hole is made of relatively great length, and preferably inclined to the horizontal, to secure a leisurely entrance of air as distinguished from 45 the more forcible blowing in of air which may occur with the usual forms of ventilation holes, where the length of the hole is seldom greater and often less than the diameter thereof. A current of air passing beneath the magneto housing cannot readily enter into the magneto under 50 any appreciable pressure and thus dust and dirt are not forced or blown in. Some dust and dirt will naturally enter the hole 51 but much of it will tend to cling to the wall of the hole because 55 of the lack of pressure in the entering air and such dust and dirt as does enter the housing will not be forced against the magneto parts,—such for example as the parts of the timer,—but will be gently deposited in the housing in out of the 60 way locations, where it will do no harm.

The invention thus affords improvements in magneto structure which are calculated to protect the moving parts of the magneto against damage from lack of lubrication and from dust 65 and dirt. The bearing arrangement and the mounting provisions have been incorporated in a simple and practically fool-proof structure capable of manufacture at low cost and yet exceedingly effective and calculated to give a long 70 useful life without requiring any attention on the part of the operator.

What we claim is:

1. The combination with the crankcase of an engine and an engine-driven member rotatable 75

therein, said crankcase having an opening adjacent said member, of a magneto including a housing, a rotor and a stator mounted therein and a shaft to which said rotor is fixed, said 5 housing having a flange secured to said crankcase and closing said opening, said shaft extending out of the housing through said flange and into the crankcase, a driving connection between said shaft and member, and bearing means for 10 rotatably supporting said rotor shaft and constituting the sole support for said shaft, said bearing means located in said housing between the rotor and said flange, said housing having passages leading from the crankcase side of said 15 flange to said bearing means and from the latter back to said side of said flange for the circulation of lubricant from the crankcase to said means.

2. The combination with the crankcase of an engine and an engine driven gear rotatable therein, said crankcase having an opening adjacent said gear, of a magneto including a housing, a rotor and a stator mounted therein, and a shaft to which said rotor is fixed, said housing having 20 a flange secured to the crankcase and closing said opening, said shaft extending out of the housing through said flange and projecting beyond the flange into said crankcase, a gear on the projecting end of said shaft for driving engagement with the first-named gear, impulse driving mechanism for actuating said shaft from said gear and located between the gear and flange in position to be lubricated from the splash in the crankcase, bearing means in said housing for rotatably supporting said shaft and constituting the sole support therefor, said housing having 25 passages leading from the crankcase side of said flange to the bearing means for supplying lubricant from the crankcase thereto and other passages leading from the bearing means to said side of said flange for returning lubricant to the crankcase.

3. The combination with the crankcase of an engine and an engine-driven member rotatable therein, said crankcase having an opening adjacent said member, of a magneto including a housing, a rotor and a stator mounted therein, breaker point mechanism including an actuating cam, and a shaft to which said rotor and cam are fixed, said housing having a flange secured 45 to said crankcase and closing said opening, said shaft extending out of the housing through said flange and into the crankcase, a driving connection between said shaft and member, and bearing means for rotatably supporting said rotor shaft and constituting the sole support for said shaft, said bearing means located in said housing between the rotor and said flange, said housing having 50 passages leading from the crankcase side of said flange to said bearing means and from the latter back to said side of said flange for the circulation of lubricant from the crankcase to said means.

4. The combination with the crankcase of an engine and an engine-driven member rotatable therein, said crankcase having an opening adjacent said member, of a magneto including a housing, a rotor and a stator mounted therein and a horizontal shaft to which said rotor is fixed, said housing having a flange disposed at 55 right angles to the axis of said shaft and secured to said crankcase and closing said opening, said shaft extending out of the housing through said flange and into the crankcase, a driving connection between said shaft and member, said hous-

ing having a recess therein coaxial with said shaft and extending inwardly from the crankcase side of said flange to the rotor, axially spaced bearings one near said flange and one near the rotor mounted in said recess and rotatably supporting said shaft and constituting the sole bearing means therefor, sealing means located between the rotor and the adjacent bearing to restrain the passage of lubricant from said recess to the rotor, said housing having a lubricant feed passage extending from the crankcase side of said flange in downwardly sloping relation to said recess at a point intermediate said bearings, said housing also having a lubricant drain passage extending from said recess at a point intermediate 15 said bearings in downwardly sloping relation to and opening through the crankcase side of said flange.

5. The combination with the crankcase of an engine and an engine-driven member rotatable therein, said crankcase having an opening adjacent said member, of a magneto including a housing, a rotor and a stator mounted therein and a horizontal shaft to which said rotor is fixed, said housing having a flange disposed at right 20 angles to the axis of said shaft and secured to said crankcase and closing said opening, said shaft extending out of the housing through said flange and into the crankcase, a driving connection between said shaft and member, said housing having a recess therein coaxial with said shaft and extending inwardly from the crankcase side of said flange to the rotor, axially spaced 25 bearings one near said flange and one near the rotor mounted in said recess and rotatably supporting said shaft and constituting the sole bearing means therefor, sealing means located between the rotor and the adjacent bearing to restrain the passage of lubricant from said recess to the rotor, said housing having a lubricant feed passage extending from the crankcase side of said flange in downwardly sloping relation to said recess at a point intermediate said bearings, said housing also having a lubricant drain passage 30 extending from said recess at a point intermediate said bearings in downwardly sloping relation to and opening through the crankcase side of said flange, said housing having a second lubricant drain passage leading from the space 35 between the sealing means and the adjacent bearing and opening through the crankcase side of said flange.

6. In a magneto, a housing, a stator and a rotor mounted therein, a shaft fixed to the rotor, said housing having a recess coaxial with said shaft and extending from one outer face inwardly toward the rotor, sealing means closing the inner end of said recess except for an opening through which the shaft passes, a mounting flange disposed at right angles to the axis of said shaft and adapted to be secured to the crankcase of an engine, said flange having an integral sleeve fitting into said recess and fixed to said housing, said shaft extending through said sleeve in spaced and coaxial relation and beyond the flange, axially spaced bearings mounted in said sleeve and forming the sole means for rotatably supporting said shaft, said housing having lubricant conducting passages extending from the flange to said bearings.

7. In a magneto, a housing, a stator and a rotor mounted therein, a shaft fixed to the rotor, said housing having a recess coaxial with said shaft and extending from one outer face inwardly toward the rotor, sealing means closing

the inner end of said recess except for an opening through which the shaft passes, a mounting flange disposed at right angles to the axis of said shaft and adapted to be secured to the 5 crankcase of an engine, said shaft extending through said recess in coaxial relation and beyond said flange, bearings for said shaft all mounted in said recess, said housing having on one side of said sealing means lubricant conducting passages extending from the flange to the bearings and having on the other side a relatively long and downwardly sloping ventilation and drain passage connecting its interior to the atmosphere.

15 8. The combination with the crankcase of an engine and an engine-driven member rotatable therein, said crankcase having an opening adjacent said member, of a magneto including a housing, a rotor and a stator mounted therein 20 and a shaft to which said rotor is fixed, said housing having a flange secured to said crankcase and closing said opening, said shaft extending out of the housing through said flange and into the crankcase, a driving connection between 25 said shaft and member, and bearing means for rotatably supporting said rotor shaft and constituting the sole support for said shaft, said bearing means located in said housing between said flange and the point of connection of the rotor 30 to said shaft, said housing having a passage leading from the crankcase side of said flange to said bearing means for the supply of lubricant from the crankcase to said means.

9. The combination with the crankcase of an 35 engine and an engine-driven member rotatable therein, said crankcase having an opening adjacent said member, of a magneto including a housing, a rotor and a stator mounted therein, breaker point mechanism including an actuating cam, 40 and a shaft to which said rotor and cam are fixed, said housing having a flange secured to said crankcase and closing said opening, said shaft extending out of the housing through said flange and into the crankcase, a driving connection 45 between said shaft and member, and bearing means for rotatably supporting said rotor shaft and constituting the sole support for said shaft, said bearing means located in said housing between said flange and the point of connection of the rotor 50 to said shaft, said housing having a passage leading from the crankcase side

of said flange to said bearing means for the supply of lubricant from the crankcase to said means.

10. The combination with the crankcase of an engine and an engine-driven member rotatable 5 therein, said crankcase having an opening adjacent said member, of a magneto including a housing, a rotor and a stator mounted therein and a horizontal shaft to which said rotor is fixed, said housing having a flange disposed at right 10 angles to the axis of said shaft and secured to said crankcase and closing said opening, said shaft extending out of the housing through said flange and into the crankcase, a driving connection between said shaft and member, said housing 15 having a recess therein coaxial with said shaft and extending inwardly from the crankcase side of said flange to the point of attachment to the rotor to said shaft, axially spaced bearings one near said flange and one near said 20 point mounted in said recess and rotatably supporting said shaft and constituting the sole bearing means therefor, sealing means located between the rotor and the adjacent bearing to restrain the passage of lubricant from said recess 25 to the rotor, said housing having a lubricant feed passage extending from the crankcase side of said flange in downwardly sloping relation to said recess at a point intermediate said bearings.

11. In a magneto, a housing, a stator and a rotor mounted therein, a shaft fixed to the rotor, said housing having a recess coaxial with said shaft and extending from one outer face inwardly toward the rotor, sealing means closing the inner end of said recess except for an opening 30 through which the shaft passes, a mounting flange disposed at right angles to the axis of said shaft and adapted to be secured to the crankcase of an engine, said flange having an integral sleeve fitting into said recess and fixed to said 35 housing, said shaft extending through said sleeve in spaced and coaxial relation and beyond the flange, axially spaced bearings mounted in said sleeve and forming the sole means for rotatably supporting said shaft, said housing having a lubricant conducting passage extending from the flange to said bearings.

WILLIAM F. BORGERD.
